UNITED STATES PATENT OFFICE:

EDWIN J. GOULD, OF FRUITVALE, CALIFORNIA.

SHOCK-ABSORBING WHEEL.

1,250,447.

Specification of Letters Patent. Patented Dec. 18, 1917.

Application filed September 23, 1916. Serial No. 121,761.

To all whom it may concern:

Be it known that I, EDWIN J. GOULD, a citizen of the United States, residing at Fruitvale, in the county of Alameda and 5 State of California, have invented certain new and useful Improvements in Shock-Absorbing Wheels, of which the following is a specification.

This invention relates to certain new and 10 useful improvements in vehicle wheels and it has for its objects primarily to provide a wheel which will absorb road shocks.

It has for a further object to provide a 15 simple and efficient construction embodying an eccentric hub, the wheel normally running true to its own center but mounted for oscillation as obstructions are met.

The device is simple in the extreme, yet 20 most reliable and efficient in its operation, not liable to injury and in practice has been found to be exceedingly durable.

Other objects and advantages of the invention will hereinafter appear and the novel features thereof will be particularly 25 pointed out in the appended claims.

The invention is clearly illustrated in the accompanying drawings, which, with the numerals of reference marked thereon, form a part of this specification, and in which

30 Figure 1 is a side elevation illustrating my invention.

Fig. 2 is a substantially central vertical section through the same.

Like numerals refer to like parts in both 35 views.

Referring to the drawing,

1 designates the axle and 2 ball bearings therefor.

3 is an eccentric within the hub proper of 40 the wheel and between this eccentric and the hub proper are the ball bearings 5.

4 is an eccentric rigid with the eccentric 3 and offset therefrom and this eccentric 4 is mounted within an eccentric opening in the 45 eccentric strap or hanger 6 which, in the present instance, is shown in the shape of an eye-bolt, the eye of which surrounds the said eccentric 4.

7 is a spring, shown in the present instance as an expanding coil spring fastened 50 at one end to the frame or chassis 8 of the vehicle and at the other end to the adjacent end of the shank of the eye-bolt, all as seen clearly in Fig. 2.

55 9 are the spokes extending radially from the hub proper and 10 is the tire of the

wheel which may be of any preferred or well-known form of construction, of metal or otherwise.

The eccentric 4 is offset with relation to 60 the axle and is mounted on said axle; on the ball bearings of which it rotates or rather oscillates as obstructions are met, the movements of the eccentric 3 being controlled by the spring 7, which spring gets its action 65 through the eccentric guide or hanger 6, it being noted that the eccentrics 3 and 4 are disposed with their greater diameters extending in opposite directions from the bore thereof in which is received the axle 1. See 70 particularly Fig. 2, the one (4) surrounded by the eye-bolt or eccentric strap 6 having its long center held upright by the spring which holds the other part of eccentric 3 opposite or downward. Thus the axle is normally held above the center of the wheel, and as the wheel strikes an obstruction and the lower half of the eccentric 3 is moved from a vertical plane backward and upward the wheel is moved bodily over the 80 obstruction. When the obstruction has been passed, the reverse action takes place and the old position of the eccentrics and axle are resumed, and as the eccentrics can freely oscillate both forward and backward there 85 is no severe action as is the case with up and down springs alone. It will be noted that if this action were carried to its extreme and the eccentric 3 is moved backward and upward until it has reached its upper center, a 90 complete reversal of the eccentric positions would take place and the eccentric 4 could be completely rotated by the spring action and the eccentric 3 would thus make a complete 95 revolution inside of the wheel and would retard the forward speed of the wheel without affecting its revolutions and at the same time would carry it upward until the center was rigid and the obstacle surmounted, when with the last half of the revolution 100 of the eccentric the speed of the wheel would be accelerated and regain what was lost.

The wheel is held in stable equilibrium by the contraction of the spring 7, which is 105 a "pull" or contracting spring of sufficient power to hold it in this position in normal smooth running, and in order to do this the spring for each wheel must be strong enough to support one-fourth of the load of the vehicle. When an obstruction is met with sufficient force to disturb the equilibrium of

one wheel at a time, the eccentric 3 is thrown backward and upward, and the eccentric 4 at the same time expanding the spring 7 and going forward, will enable the wheel 5 to surmount the obstruction without changing the position of the axle. A vehicle with these wheels could have its body supported with springs from the axle up, as in common practice; but these springs could only 10 be affected by a shock transferred to them through the wheel and axle. By rotating the eccentrics 3 and 4 or reversing their positions, a more stable equilibrium could be secured if it were the only object in view; 15 but the object is to secure resilience and equilibrium and the spring 7 does this by offering resilient resistance to obstructions of the wheel by acting first through the strap or hanger 6 and the support 8 to the 20 eccentrics 4 and 3. If the spring 7 were removed, the eccentrics 4 and 3 would then reverse their positions from the weight of the body of the vehicle, but there would be 25 no resilient action of the wheel beyond a possible slight oscillation on meeting an obstruction.

It is evident that the relative position of the parts, as above described, is not necessary, as the eccentrics can be placed at any 30 angle to each other.

The body of the vehicle will obviously be supported or suspended above the axle in some conventional way such as a leaf spring, or it may be rigid means.

25 The full lines in Fig. 1 indicate the normal position of the parts and the dotted lines indicate their position when the wheel is surmounting an obstruction.

Various modifications in detail, such, for 30 instance, as the replacing of the eccentrics by cranks and other forms of devices for causing oscillation of the wheel upon its meeting with an obstruction, may be resorted to without departing from the spirit of the invention or sacrificing any of its advantages. I, therefore, do not intend to restrict myself to the particular construction of parts etc. as herein disclosed, but reserve the right to make such changes, variations and modifications as come properly within the scope of 35 the protection prayed.

What is claimed as new is:—

1. A shock absorbing wheel comprising an eccentric within the hub, an axle mounted in 40 said eccentric, and an eccentric rigid with the first-named eccentric, said eccentrics having their greater diameters extending in opposite directions from the bore, one of said eccentrics receivable within the hub of a wheel, and a resiliently supported bearing for the other eccentric designed to maintain said eccentrics in normal position.

2. A shock absorbing wheel comprising an eccentric within the hub, an axle mounted in said eccentric and an eccentric rigid with the first-named eccentric and having a portion 45 at an angle thereto and resilient means

designed to maintain said eccentrics in normal position.

3. A shock absorbing wheel comprising an eccentric within the hub, an axle mounted in said eccentric, an eccentric rigid with the first-named eccentric and having a portion at an angle thereto, and an eccentric guide for the second-named eccentric and resilient means designed to maintain said eccentrics in normal position.

4. A shock absorbing wheel comprising an eccentric within the hub, an axle mounted in said eccentric, an eccentric rigid with the first-named eccentric and having a portion at an angle thereto, an eccentric guide for the second-named eccentric and resilient means designed to maintain said eccentrics in normal position.

5. In a shock absorbing wheel, a hub proper, an eccentric hub within the same, an axle mounted in said eccentric hub and a spring-controlled eccentric rigid with and having a portion at an angle to the first-named eccentric.

6. In a shock absorbing wheel, a hub proper, an eccentric revolubly mounted therein, a second eccentric rigid with the first-named eccentric and having a portion at an angle thereto, an eccentric guide for the last-named eccentric, and a spring connecting the same with a relatively fixed part.

7. In a shock absorbing wheel, a hub proper, an eccentric revolubly mounted therein, a second eccentric rigid with the first-named eccentric and having a portion at an angle thereto, an eccentric guide for the last-named eccentric, a spring connecting the same with a relatively fixed part, and an axle having a bearing in both eccentrics.

8. A shock absorbing wheel embodying a plurality of eccentrics rigid with each other and having their greater diameters extending in opposite directions from the bore, one of said eccentrics receivable within the hub of a wheel, and a resiliently supported bearing for the other eccentric designed to maintain said eccentrics in normal position.

9. A shock absorbing wheel embodying a plurality of eccentrics rigid with each other and having their greater diameters extending in opposite directions from the bore, one of said eccentrics receivable within the hub of a wheel, a resiliently supported bearing for the other eccentric, and means for normally supporting the axle above the center of the wheel.

10. A shock absorbing wheel having a hub, an eccentric within the hub, a second eccentric rigid with the first eccentric with the greater diameters of said eccentrics extending in opposite directions from the bore, and an axle supported in said bore and normally held above the center of the wheel and resilient means designed to maintain said eccentrics in normal position.

11. A shock absorbing wheel having a hub, an eccentric within the hub, a second eccentric rigid with the first eccentric with the greater diameters of said eccentrics extending in opposite directions from the bore, an axle supported in said bore and normally held above the center of the wheel, and resilient means designed to maintain said eccentrics in normal position for and allowing said wheel to oscillate upon meeting an obstruction.

12. A shock absorbing wheel embodying an axle, and a wheel mounted thereon with the axle disposed eccentrically and normally supported above the center of the wheel, an eccentric within the hub of the wheel, a second eccentric eccentrically disposed within the first-named eccentric, a guide exteriorly of the wheel for the last-named eccentric

and resilient means designed to maintain 20 said eccentrics in normal position.

13. A shock absorbing wheel embodying an axle, and a wheel mounted thereon with the axle disposed eccentrically and normally supported above the center of the wheel, an 25 eccentric within the hub of the wheel, a second eccentric eccentrically disposed within the first-named eccentric, a guide exteriorly of the wheel for the last-named eccentric, and a spring interposed between the 30 said guide and a relatively fixed support.

In testimony whereof I affix my signature in the presence of two witnesses.

EDWIN J. GOULD.
